UNITED STATES PATENT OFFICE.

TULLY R. CORNICK, OF PETALUMA, CALIFORNIA.

AUTOMOBILE LOCK SYSTEM.

Application filed January 3, 1921. Serial No. 434,564.

To all whom it may concern:

Be it known that I, TULLY R. CORNICK, a citizen of the United States, residing at Petaluma, in the county of Sonoma and 5 State of California, have invented certain new and useful Improvements in Automobile Lock Systems, of which the following is a specification.

This invention relates to a locking apparatus for fuel feed system of automobiles.

The primary object of the invention is the provision of a locking means suitable for use for either gravity, pressure, or vacuum feed systems.

15 A further object is to provide means for draining the vacuum tank when the main system has been cut off to prevent the use of the fuel in the gravity compartment of the vacuum tank.

20 A further object is to arrange in the vacuum system an auxiliary tank in the main feed line, which will feed by gravity a given amount of fuel to the vacuum tank for initial starting purposes, where, for instance, 25 the carburetor may have been drained by an attempt to start the car when the main feed line is locked.

A further object of my invention is to provide a system which, while it is effectually locked against theft, will however permit of a slight movement of the car when it is desirable perhaps to move the car a moderate distance in case of fire.

30 In the accompanying drawings—

35 Fig. 1 is a diagrammatic view showing my invention as applied to the vacuum system;

Fig. 2 is a diagrammatic view showing my invention as applied to the gravity or pressure system;

40 Fig. 3 is a detail sectional view of the combination locking valve;

Fig. 4 is an enlarged detail view of the drainage tank.

45 Fig. 5 is a side elevation of the plunger for actuating the valve of the lock.

As indicated in Fig. 1, the usual vacuum system comprises a supply tank 1, a vacuum tank 2, and a carburetor 3, the fuel being fed from the supply tank to the vacuum 50 tank 2 through the action of vacuum produced by the engine. As undoubtedly understood, when a certain amount of fuel is drained into the upper half of the vacuum

tank 2, the vacuum ceases to operate through a float, and until the level of the fuel in said tank reaches a certain lower level it feeds to the carburetor by gravity alone. When this certain lower level is reached, the vacuum is again operated until the original higher level is again reached, whereupon the 60 operation is repeated.

4, indicates the combination locking valve compartment interposed between the supply tank 1 and the vacuum tank 2. 5, indicates an auxiliary supply tank communicating 65 with the locking valve compartment 4, the auxiliary supply tank being connected by feed pipe 6 to the main supply, and the locking valve compartment 4 being connected by feed line 7 to the vacuum and tank 2. 70 The locking valve arranged in the locking-valve compartment 4 preferably consists of a body portion 8 having a countersunk portion 8', which is adapted to receive a cap 9.

Arranged in the chamber 8' is a plunger 75 10 having flexibly secured to its outer face a flat valve 11. 12, indicates a plunger-stem extending through the body portion 8 and adapted to receive on the outer end thereof an actuating-member 13 which is controlled 80 by a handle 14 arranged in the compartment 4 and controlled by combination lock 16.

Ordinarily the supply of fuel is carried from the main supply tank 1 to the auxiliary tank 5 through the combination compartment 4, and thence to the vacuum tank 2. The purpose of the auxiliary supply tank 5 is to supply enough fuel to the carburetor by gravity in case some unauthorized person has attempted to start the car 90 during the absence of the operator and drained off the carburetor completely. To accomplish this, the intake 18 of the supply-tank is arranged at the upper edge at one end, and the outlet 19 is arranged at the lower edge of the opposite end. Connected to the outlet is a stand-pipe 20 provided with an opening at its extreme upper end near the top of the tank.

Thus it will be seen that ordinarily the 100 tank is fully charged with fuel before it finally passes through the outlet 19. In case it is desirable to empty the contents of the auxiliary tank into the vacuum tank, a similar valved nipple 21 is arranged at the bottom of the stand-pipe having an actuating 105

lever 22 extending outside of the tank, whereby the tank may be drained by gravity of its contents.

In view of the gravity part of the vacuum tank 2 always holding sufficient gas to allow the car to operate for some miles, it becomes necessary not only to close the gasoline line from the main tank 1, but it is also necessary to remove all of the gasoline from the gravity compartment of the vacuum tank. To effect this, a drainage tank 23 is arranged at an elevation sufficiently lower than the vacuum tank to allow the gasoline therein to drain out. This drainage tank is preferably actuated by a valve 24 controlled by an actuating-stem 25 extending up through the dash of the car. Actuated by this actuating stem is an air vent 26, arranged at the upper end of the drainage tank, which is simultaneously opened with the opening of the valve 24 to allow the drainage tank to fill properly.

It is obvious that some means must be provided for emptying the drainage tank at intervals, in order that it may properly function. To accomplish this, a by-pass 27 is adapted to extend well into the bottom of the drainage-tank 23, and is connected to the main supply tank 6. Thus when the operator releases the combination valve to start the engine, he first closes valve 24 and the air valve 26 by the actuation of the actuating-stem 25, whereupon the suction affected by the engine has the effect of draining the drainage-tank.

As disclosed in Fig. 2, the system comprises the main supply tank 1, the combination locking compartment 4, and the carburetor 3, it being observed that the carburetor is fed by gravity from the main supply in which case it is only necessary to cut off the supply by actuation of the combination lock 16.

In the vacuum system, the operation is as follows:—When bringing the car to a stop, the operator pulls up on the actuating-stem 25, thereby opening the air-vent of the drainage tank A, and opening the needle-valve 24, which effects the drainage of the lower gravity compartment of the vacuum tank, after which the combination valve is manipulated to effect the closing of the main line between the supply and the main tank. Upon starting up the car, the actuating-stem 25 is pushed downwardly, closing the vent 26, closing the valve 24, after which the combination lock is released, opening the main supply line to the vacuum tank 2, the engine being provided with sufficient fuel for starting by the contents of the carburetor. The starting of the engine produces sufficient vacuum to start the circulation of fuel through the system. Should the operator in starting discover that an attempt has been made to start the motor and the carburetor exhausted

of its supply, the actuating-valve 22 of the auxiliary tank 5 is actuated, whereupon the contents thereof are delivered by gravity to the vacuum tank 2, and thence to the carburetor, giving a sufficient charge to start the engine, after which the usual system is brought into operation.

I claim:

1. In a locking apparatus, the combination with a fuel supply tank and a carburetor, a feed line therebetween, of a locking device comprising a tank interposed in the feed line, normally maintaining a reserve supply of fuel, means for shutting off the normal flow through the tank, and means for draining the reserve supply from said tank.

2. In a locking apparatus, the combination with a vacuum line, a vacuum tank, and a carburetor fuel line, of a lock connected in the vacuum line adapted to close same when turned in one direction, and an auxiliary supply tank connected in the vacuum line between the lock and supply-tank adapted to feed by gravity a given quantity of gasoline to the vacuum tank.

3. In a locking apparatus, the combination with a vacuum line, a vacuum tank, and a carburetor fuel line, of a lock connected in the vacuum line adapted to close the same when turned in one direction, and a drainage tank connected to the vacuum tank, whereby the latter may be emptied of its contents.

4. In a locking apparatus, the combination with a vacuum line, a vacuum tank, and a carburetor fuel line, of a lock connected in the vacuum line adapted to close the same when turned in one direction, a drainage tank connected to the vacuum tank, whereby the latter may be emptied of its contents, and means connected with said branch tank and vacuum line whereby the drainage tank may be emptied upon the initial starting of the engine.

5. In a locking apparatus, the combination with a vacuum line, a vacuum tank, and a carburetor fuel line, of a lock connected in the vacuum line adapted to close same when turned in one direction, an auxiliary supply tank connected in the vacuum line between the lock and the supply tank adapted to feed by gravity a given quantity of gasoline to the vacuum tank, and a drainage tank connected to the vacuum tank whereby the latter may be emptied of its contents.

6. In a locking apparatus, the combination with a vacuum line, a vacuum tank and a carburetor fuel line, of a lock connected in the vacuum line adapted to close same when turned in one direction, an auxiliary supply tank connected in the vacuum line between the lock and the supply tank, adapted to feed by gravity a given quantity of gasoline to the vacuum tank, a drainage tank connected to the vacuum tank, whereby the

latter may be emptied of its contents, and means connected with said drainage tank and vacuum line, whereby the drainage tank may be emptied upon the initial starting of 5 the engine.

7. In a locking apparatus, the combination with a vacuum line, a vacuum tank, a carburetor fuel line, a lock connected in the 10 vacuum line adapted to control the same when turned in one direction comprising a body portion, provided with inlet and outlet ports, a reciprocating plunger therein controlling said outlet port, and a combination lock controlling said reciprocating 15 plunger, whereby the plunger may be locked in an open or closed position.

8. In a locking apparatus, the combination with a vacuum line, a vacuum tank, a carburetor fuel line, a lock connected in the 20 vacuum line adapted to control the same when turned in one direction comprising a body portion, provided with inlet and outlet ports, a reciprocating plunger therein controlling said outlet port, a combination lock controlling said reciprocating plunger, whereby the plunger may be locked in an 25 open or closed position, and a drainage tank connected to the vacuum tank adapted to empty the latter of its contents by gravity, 30 a valve interposed between the vacuum tank and the drainage tank, an air-vent arranged in the top of said drainage tank, and a common actuating means to both of said valves, whereby they are simultaneously 35 opened and closed.

9. In a locking apparatus, the combination with a vacuum line, a vacuum tank, and a carburetor fuel line, of a lock connected to the vacuum line adapted to close 40 the same when turned in one direction, said lock comprising a hollow body portion provided with inlet and outlet ports, a reciprocating valve arranged therein adapted to control said outlet port, a combination locking means controlling said reciprocating valve whereby the latter may be locked in either an open or closed position, and a drainage tank connected to the vacuum tank, whereby the latter may be emptied of its 45 contents by gravity, a valve interposed between the vacuum tank and the drainage tank, an air-valve arranged in the upper end of said drainage tank, means common to both of said valves for simultaneously opening and closing the same and means connected with said drainage tank and vacuum line whereby the drainage tank may be emptied of its contents upon the initial starting of the engine.

10. In a locking apparatus, the combination with a vacuum line, a vacuum tank, and a carburetor fuel line, of a lock connected to the vacuum line adapted to close the same when turned in one direction, said lock comprising a hollow body portion provided with 60 inlet and outlet ports, a reciprocating valve arranged therein adapted to control said outlet port, a combination locking means controlling said reciprocating valve, whereby the latter may be locked in either an 65 opened or closed position, an auxiliary tank connected in the vacuum line between the lock and the supply tank adapted to feed by gravity a given quantity of gasoline to the vacuum tank, and a drainage tank connected to the vacuum tank, whereby the latter may be emptied of its contents by 70 gravity, a valve interposed between the vacuum tank and the drainage tank, an air-valve arranged in the upper end of said drainage tank, means common to both of 75 said valves for simultaneously opening and closing the same, and means connected with said drainage tank and vacuum line, whereby the drainage tank may be emptied of 80 its contents upon the initial starting of the engine.

11. In a locking apparatus, the combination with a fuel supply tank and a carburetor, a feed line therebetween including an auxiliary tank, means for maintaining a 85 reserve supply of fuel in said auxiliary tank, during the normal operation of the system, including a standpipe in the tank open at the top, of means for interrupting the flow 90 through the auxiliary tank and the standpipe, and additional means for draining the reserve supply of fuel from the auxiliary tank.

12. In a locking apparatus, the combination with a fuel supply tank and a carburetor, a feed line therebetween, of a locking device comprising a tank interposed in the feed line and normally maintaining a 100 reserve supply of fuel during the normal functioning of the system including a standpipe open at the upper end and connected at the lower end with the feed line, and means for draining the reserve supply fuel in said auxiliary tank into said feed line, said last- 105 mentioned means including a valve nipple connected with the bottom of the standpipe, a valve in the nipple, an actuating lever extending beyond the tank, and means for locking said lever in a desired position.

In testimony whereof I affix my signature.

TULLY R. CORNICK.
